UNITED STATES PATENT OFFICE.

THOMAS J. MORGAN, OF KINGSTON, PENNSYLVANIA.

CAR-AXLE BOX.

SPECIFICATION forming part of Letters Patent No. 657,744, dated September 11, 1900.

Application filed July 21, 1900. Serial No. 24,409. (No model.)

To all whom it may concern:

Be it known that I, THOMAS J. MORGAN, a citizen of the United States, residing at Kingston, in the county of Luzerne and State of Pennsylvania, have invented certain new and useful Improvements in Car-Axle Boxes; and I do hereby declare the following to be a full, clear, and exact description of the invention, such as will enable others skilled in the art to which it appertains to make and use the same.

This invention relates to axle-boxes for cars or trucks used on mining-railroads and other places; and it consists in the novel construction and combination of the parts hereinafter fully described and claimed.

In the drawings, Figure 1 is a sectional view of a portion of a car provided with an axle-box according to this invention. Fig. 2 is an end view of the axle-box drawn to a larger scale.

A is a portion of the car or truck frame.

B is a portion of a car-axle, and C is one of the car-wheels.

The axle-box is formed of two parts—namely, a bracket D and a bearing-block E. The bracket D is secured to the car-frame by bolts b and is provided with a forked guide d at its lower part, having inwardly-projecting lugs d', which form a stop at its lower end. The bracket is also provided with a lug c, which projects from the upper part of the side which is farthest from the car-wheel. The bearing-block E engages loosely with the forked guide d and is prevented from dropping out of it when the car-body is raised by means of the lugs d', which only permit the bearing-block to be separated from the bracket to a limited extent. The bearing-block E has an annular projection f on one side, which engages with a socket f' formed in the hub of the car-wheel, so that no dirt can get into the bearing on the side next to the car-wheel. The axle is journaled in the bearing-block and in the projection f.

F is a chamber for oil and waste or other approved lubricating material. This chamber is formed in the bearing-block E at the end of the car-axle, and it has an opening 50 at its top which is normally closed by the

bracket D, so that no dirt can get through it into the bearing.

G is a wedge-shaped projection on the end of the bearing-block under the lug c on the bracket. This projection is arranged with its apex uppermost, and H is a split pin which is driven through a hole in the lug c onto the projection G. The projection spreads the split pin and prevents it from rising. The split pin prevents the bearing-block from sliding endwise in the bracket and permits the bracket to be raised to fill the chamber F with oil. Flanges h are also formed on the bearing-block and bear against the bracket D. These flanges assist in holding the bearing-block and axle in position.

This axle-box forms a cheap and efficient bearing for the axles of mining-trucks which work in much dirt, which requires to be kept out of their axle-bearings.

What I claim is—

1. In an axle-box, the combination, with a bracket having a forked guide, of a bearing-block movable vertically in the said guide and having a chamber for lubricant which is normally closed by the said bracket, and having also a wedge-shaped projection at one end, and a split pin engaging with the said bracket and projection and preventing the bearing-block from sliding endwise out of the bracket, substantially as set forth.

2. In an axle-box, the combination, with a bracket having a forked guide provided with a stop at its lower part, of a bearing-block which is slidable vertically to a limited extent in the said guide, said block being provided with a chamber for lubricant which is normally closed by the said bracket, and means for preventing the bearing-block from sliding endwise out of the bracket, substantially as set forth.

3. In an axle-box, the combination, with a bracket having a forked guide, of a bearing-block having a chamber for lubricant near one end which is normally closed by the said bracket, and an annular projection at the other end for engaging with a recess in the adjacent car-wheel, substantially as set forth.

4. In an axle-box, the combination, with a bracket having a forked guide and a pro-

jeeting lug, of a bearing-block movable vertically in the said guide and having a chamber for lubricant which is normally closed by the said bracket, said block having also 5 flanges which prevent it from sliding endwise in one direction and a wedge-shaped projection arranged under the said lug, and a split pin passed through a hole in the said lug and engaging with the said projection

and preventing the said block from sliding endwise in the other direction, substantially as set forth.

In testimony whereof I affix my signature in presence of two witnesses.

THOMAS J. MORGAN.
